[57] CLAIM

The ornamental design for a planter, as shown and described.

DESCRIPTION

FIG. 1 is a front perspective view of a planter showing my new design, the rear being identical;

FIG. 2 is an end elevational view thereof, the end opposite being identical;

FIG. 3 is a top plan view thereof;

FIG. 4 is a fragmentary bottom plan view thereof, it being understood that the surface as shown is continuous throughout.
